SLIDE PROJECTOR

Arthur H. Crapsey, Jr., Rochester, N. Y., assignor to
Eastman Kodak Company, Rochester, N. Y., a cor-
poration of New Jersey

Application September 10, 1954, Serial No. 32,234

Term of patent 3½ years

(Cl. D61—1)

Fig. 1

Fig. 2

To all whom it may concern:

Be it known that I, Arthur H. Crapsey, Jr., a citizen of the United States of America, residing in Rochester, in the county of Monroe and State of New York, have invented a new, original, and ornamental Design for a Slide Projector, of which the following is a specification, reference being had to the accompanying drawings, forming a part thereof, in which:

Fig. 1 is a perspective view of a slide projector showing my new design and showing portions of the front, side and top; and

Fig. 2 is a perspective view of the slide projector shown

in Fig. 1 taken from the rear, the top and the opposite side from that shown in Fig. 1.

I claim:

The ornamental design for a slide projector, as shown.
